[57] CLAIM

The ornamental design for a table lamp, substantially as shown and described.

DESCRIPTION

FIG. 1 is a perspective view of a table lamp showing my new design, the shade and support being shown in broken lines for illustrative purposes only;

FIG. 2 is a front elevational view thereof on an enlarged scale, the rear being a mirror image;

FIG. 3 is a top plan view thereof on an enlarged scale;

FIG. 4 is a bottom plan view thereof on an enlarged scale;

FIG. 5 is a side elevational view thereof on an enlarged scale, the opposite side being a mirror image.

FIG. 1

FIG. 2

FIG. 3

FIG. 4

FIG. 5
